(57) **CLAIM**

The ornamental design for a tablet sleeve, as shown and described.

DESCRIPTION

FIG. 1 is a top, front, left side perspective view of a tablet sleeve showing our new design;

FIG. 2 is a front elevation view thereof;

FIG. 3 is a left side elevation view thereof;

FIG. 4 is a top plan view thereof;

FIG. 5 is a bottom plan view thereof;

FIG. 6 is a rear elevation view thereof;

FIG. 7 is a right side elevation view thereof; and,

FIG. 8 is a top, front, left side perspective view of the tablet sleeve shown in an alternate position.

The broken lines represent stitching on the tablet sleeve and form part of the claimed design.
